FIG. 2

FIG. 1

FIG. 3

FIG. 4

FIG. 1 is a front view in elevation of a wall thermostat embodying my new design;

FIG. 2 is a top plan view of the thermostat shown in FIG. 1;

FIG. 3 is a side elevational view of the wall thermostat; and

FIG. 4 is a sectional view taken substantially along line 4-4 of FIG. 3 showing the contour of the front panel and sides of the wall thermostat;

The bottom view of the wall thermostat is substantially the same as the top view shown in FIG. 2.

In FIG. 1 the cross hatching indicates the color brown and the remainder of the front panel is of a metallic or similar finish.

This application is a divisional application of Ser. No. D. 2,191, filed May 6, 1966, and now patent D. 210,803, granted Apr. 16, 1968.

What I claim is:

The ornamental design for a wall thermostat, substantially as shown and described.
